UNITED STATES PATENT OFFICE.

RAYMOND N. EHRHART, OF PITTSBURG, PENNSYLVANIA, ASSIGNOR TO THE WESTINGHOUSE MACHINE COMPANY, A CORPORATION OF PENNSYLVANIA.

ELASTIC-FLUID TURBINE.

No. 868,768.

Specification of Letters Patent.

Patented Oct. 22, 1907.

Application filed April 12, 1905. Serial No. 255,114.

To all whom it may concern:

Be it known that I, RAYMOND N. EHRHART, a citizen of the United States, and a resident of Pittsburgh, in the county of Allegheny and State of Pennsylvania, 5 have invented a new and useful Improvement in Elastic-Fluid Turbines, of which the following is a specification.

This invention relates to elastic fluid turbines, and, as an object, has the production of an extremely simple 10 and compact machine of this class in which high efficiencies may be obtained. This, as well as other objects, I attain by means of the turbine described in the specification and illustrated in the drawings forming a part of this application, and throughout which similar elements are denoted by like characters.

In the drawings, Figure 1 is a longitudinal section of the upper half of a turbine embodying this invention, and Fig. 2 is an enlarged view in developed section of one half of the turbine; this view illustrates the 20 nozzle and blade layout.

The turbine illustrated is bi-laterally symmetrical and is known as a double flow machine, and consists of an outer casing or stator 3 and a rotor or rotating element 4 mounted on a shaft 5 journaled within suitable 25 bearings, and which projects through the ends of the casing.

Double flow nozzle blocks 6 are secured to the interior of the casing and are arranged around its inner periphery at suitable intervals. Nozzles 8 are formed in 30 the blocks and communicate with an annular motive fluid chamber 7 which surrounds the turbine and centrally between the ends of the casing. The nozzles 8 are over-compounded and expand the motive fluid down to exhaust pressure.

35 A portion only of the velocity energy due to the nozzle expansion is absorbed in a single moving row of impulse blades 9, carried by the rotor, and the steam leaving the impulse blades collects in a transforming receiving chamber 10, the mouth of which opposite 40 the several series of nozzles, is provided with vanes 11 for preventing the steam issuing from the impulse blades from rotating therewith.

The transformation receiving chamber 10 is so sized and proportioned that the velocity or flow energy of 45 the steam entering it is re-transformed into pressure. The fluid from the transformation chamber passes through a section comprising alternate annular rows of stationary vanes 12 and moving blades 13, whereby it is fractionally expanded down to the exhaust pressure. 50 sure: the expansions occurring both between the vanes in the stationary rows and the blades in the moving rows.

It will be understood that various changes may be made in this turbine without departing from the spirit 55 of this invention.

Between the transformation receiving chamber 10 and the section employing the guide vanes 12 and blades 13, another section may be interposed similar to the primary section or stage, or, if desired, a section may be interposed employing instrumentalities whereby a portion of the thermal energy of the re-converted fluid is transformed into kinetic energy in the form of velocity and either wholly absorbed in a single moving row of impulse blades, or fractionally abstracted in a plurality of moving rows of impulse blades together 60 with suitable intermediate guide vanes. If desired, the section employing the stationary guide vanes 12 and the moving blades 13 may be substituted by one or more sections, in each of which the thermal energy of the fluid entering it may be converted into kinetic 65 energy in the form of velocity and either wholly absorbed in a single row of moving impulse blades or fractionally abstracted in a plurality of rows of moving impulse blades and suitable intermediate guide vanes.

It will be understood that this invention is not limited to a double flow machine, but may be utilized in a single flow machine employing suitable means for balancing the rotor end thrust. It will also be understood that the same is not limited to a turbine utilizing steam, 70 as other elastic fluids may be utilized.

Having thus described this invention, what I claim as new and useful and desire to secure by Letters Patent is:

1. In an elastic fluid turbine, agents whereby the thermal energy of the working fluid is converted into kinetic 80 energy in the form of velocity and a portion only of the energy due thereto is absorbed, means for converting the remaining velocity energy into pressure and instrumentalities whereby the fluid issuing from said means is fractionally expanded.

2. In an elastic fluid turbine, a supply passage, a fluid-discharge nozzle communicating therewith arranged to convert the thermal energy of the working fluid into kinetic energy in the form of velocity, moving blades communicating with said nozzle arranged to abstract a portion 90 of said kinetic energy, a reconverting chamber communicating with said blades for converting the remaining portion of the velocity energy into pressure energy, and means for expanding the fluid issuing from said chamber and abstracting the available energy by reaction.

3. In an elastic fluid turbine, a fluid-supply passage, fluid discharge nozzles communicating therewith adapted to convert the thermal energy of the working fluid into kinetic energy in the form of velocity, moving blades adapted to abstract a portion of said kinetic energy, a reconverting chamber provided with guide vanes communicating with said blades, alternate rows of stationary vanes and moving blades communicating with said chamber whereby the fluid issuing from said chamber is fractionally expanded and the available energy abstracted by impact 100 and reaction.

4. In an elastic fluid turbine, agents whereby the thermal energy of the working fluid is converted into kinetic energy in the form of velocity and a portion only of said energy due thereto is absorbed, means for converting the 110 remaining velocity energy into pressure energy and instru-

5. In an elastic fluid turbine, agents whereby the thermal energy of the working fluid is converted into kinetic energy in the form of velocity and a portion only of said energy due thereto is absorbed, means for converting the remaining velocity energy into pressure energy and alternate rows of stationary vanes and moving blades communicating with said means whereby the fluid issuing therefrom is fractionally expanded and the available energy abstracted by impact and reaction.
6. In an elastic fluid turbine, a fluid-supply passage, fluid-discharge nozzles communicating therewith and arranged to convert the thermal energy of the working fluid into kinetic energy in the form of velocity, moving blades communicating with said nozzles arranged to abstract a portion of said kinetic energy, means for converting the remaining kinetic energy into pressure energy and instrumentalities whereby the fluid issuing from said means is fractionally expanded.
7. In an elastic fluid turbine, agents whereby the thermal energy of the working fluid is converted into kinetic energy in the form of velocity and a portion only of said energy due thereto is absorbed, means for converting the remaining velocity energy into pressure energy and instrumentalities whereby the thermal energy of the fluid issuing from said means is fractionally expanded and the available energy abstracted by reaction.
8. In an elastic fluid turbine, agents whereby the thermal energy of the working fluid is converted into kinetic energy in the form of velocity and a portion only of the energy due thereto is abstracted, means for converting the remaining velocity energy into pressure energy and instrumentalities whereby the pressure energy of the fluid issuing from said means is fractionally expanded and the available energy abstracted by impact and reaction.
9. In an elastic fluid turbine, agents whereby the thermal energy of the working fluid is converted into kinetic energy in the form of velocity and a portion only of the energy due thereto is abstracted, means for converting the remaining velocity energy into pressure energy and instru-

- mentalities whereby the thermal energy of the fluid issuing from said means is abstracted by impact and reaction.
10. In an elastic fluid turbine, a fluid-supply passage, fluid discharge nozzles communicating therewith adapted to convert the thermal energy of the working fluid into kinetic energy in the form of velocity, moving blades adapted to abstract a portion of said kinetic energy, a reconverting chamber communicating with said blades, alternate rows of stationary vanes and moving blades communicating with said chamber whereby the fluid issuing therefrom is fractionally expanded and the available energy abstracted by impact and reaction.
11. In an elastic fluid turbine, a fluid-supply passage, fluid discharge nozzles communicating therewith adapted to convert the thermal energy of the working fluid into kinetic energy in the form of velocity, moving blades adapted to abstract a portion of said kinetic energy, a reconverting chamber communicating with said blades, alternate rows of stationary vanes and moving blades communicating with said chamber whereby the fluid issuing therefrom is expanded and the available energy abstracted by impact and reaction.
12. In an elastic fluid turbine, a supply passage, fluid discharge nozzles communicating therewith adapted to convert the thermal energy of the working fluid into kinetic energy in the form of velocity, alternate rows of stationary directing vanes and moving blades communicating therewith and adapted to abstract a portion of the kinetic energy, a reconverting chamber communicating with said blades and vanes for converting the remainder of the velocity energy into pressure energy and alternate rows of stationary vanes and moving blades communicating with said chamber whereby the fluid issuing therefrom is fractionally expanded and the available energy abstracted by impact and reaction.

In testimony whereof, I have hereunto subscribed my name this eleventh day of April, 1905.

RAYMOND N. EHRHART.
